United States Patent Office

Des. 187,431
Patented Mar. 15, 1960

187,431

DRAINER BASKET

Kurt E. Christoffersen, East Hampton, Conn., assignor to Artistic Wire Products Company, Incorporated, East
Hampton, Conn., a corporation of Connecticut

Application March 13, 1959, Serial No. 54,977

Term of patent 14 years

(Cl. D44—29)

Fig. 1 is a top plan view of a drainer basket embodying my new design.

Fig. 2 is a side elevational view thereof.

Fig. 3 is an end elevational view.

Fig. 4 is a top perspective view thereof.

I claim:

The ornamental design for a drainer basket, substantially as shown.
